UNITED STATES PATENT OFFICE

2,669,483

DEVICE FOR TRANSFERRING FLUIDS

Russell H. Fletcher, Dallas, Tex., assignor of one-fourth to E. C. Fletcher, one-fourth to Velma Anderson, and one-fourth to Bettye Alexander, Dallas, Tex.

Application July 11, 1951, Serial No. 236,123

5 Claims. (Cl. 299—78)

1

This invention relates to a device for transferring fluids from one point to another and more particularly to a device having an electrically driven pump for pumping fluid through a flexible conduit woundable on an electrically driven reel.

In many applications, such as fueling of airplanes or filling of reservoirs from tanks mounted on vehicles, it is necessary to pump fluid from a tank through a flexible conduit to another tank. The flexible conduit is usually wound on a reel and a necessary length of the conduit is unwound from the reel to allow the outlet end of the conduit to reach the inlet of the tank to be filled. It is desirable to locate the controls for the electric motors which drive the pump and the reel adjacent the outlet or nozzle end of the flexible conduit in order that a single operator may control the motors while handling the nozzle end of the flexible conduit. Since the flexible conduit may be of considerable length, the conductors leading from the controls to the motors must also be quite long and are susceptible to fouling and abrading. These conductors, therefore, should preferably be secured to the flexible conduit in such a manner that they will not foul and tangle and at the same time should be protected from abrasion as the flexible conduit is dragged over the ground or around sharp corners.

Accordingly, it is an object of the invention to provide a new and improved device for transferring fluids from one point to another.

It is another object of the invention to provide a new and improved device for pumping fluids through a flexible conduit which is woundable on an electrically driven reel.

It is still another object of the invention to provide a new and improved device for pumping fluids through a flexible conduit woundable on an electrically driven reel in which the controls for the motors of the pump and of the reel are located adjacent the nozzle end of the flexible conduit in order that a single operator may control the device from the nozzle end of the flexible housing.

It is a further object of the invention to provide a new and improved flexible conduit having flexible electric conductors embedded in the wall thereof to protect the conductors from fouling and abrasion.

It is a still further object of the invention to provide a device having a pump and a reel driven by electrical motors and a flexible conduit wound on the reel and connected to the pump having electrical conductors embedded in its wall and connected to the motors and to controls mounted

2

on the flexible conduit adjacent the nozzle end of the cable.

In brief, the new and improved device for pumping fluid includes a reel rotatably mounted on a base and driven by a reversible motor. A flexible conduit is wound on the reel and has one end connected through a suitable connection to a pump also mounted on the base and driven by a second reversible motor. The other free end of the flexible conduit is provided with a conventional nozzle. In order that the motors of the pump and of the reel may be controlled by a single operator handling the nozzle, a plurality of switches are mounted on the flexible conduit adjacent the nozzle and are connected to conductors embedded in the flexible conduit which extend through the conduit to the reel. A suitable slip ring assembly is mounted on the rotatable reel and coacts with brushes on a stationary member to connect the ends of the conductors to the motors.

For a better understanding of the invention, reference may be had to the following description taken in connection with the accompanying drawing and its scope will be pointed out in the appended claims.

In the drawing,

Figure 1 is a perspective view of the pump, the reel on which the flexible conduit is wound, and the motors for operating the pump and the reel;

Figure 2 is a transverse sectional view of the conduit taken along line 2—2 of Figure 3;

Figure 3 is a longitudinal sectional view taken along the line 3—3 of Figure 2;

Figure 4 is a side elevation, with parts broken away, of the nozzle provided on the outer free end of the flexible conduit;

Figure 5 is a perspective view of the nozzle;

Figure 6 is a longitudinal sectional view of one end of the reel showing the manner in which the inner end of the flexible conduit is connected to a stationary connection and the manner in which the conductors and slip ring assembly are connected; and,

Figure 7 is a diagrammatic illustration of the electric control circuit.

Referring now to the drawing, the device 10 for transferring fluid from one point to another comprises a base 11 on which is mounted two brackets 12 and 13 for rotatably supporting the reel 14. Each bracket has two upwardly and convergently inclined legs 15 and 16 whose lower ends are secured to the base 11 by bolts 17. The upper ends of the legs of each bracket are rigidly secured, by welding or other conventional means,

to a bearing ring 18 in which is mounted a conventional ball bearing assembly 19 having stationary races 20 secured to the ring 18 and movable races 21. Each of the end disks 22 and 23 of the reel 14 has an integral outwardly extending hollow shaft 24 which abuts and extends through the movable races 21 of its associated ball bearing assembly 19. The end disks are secured to one another by longitudinal integral connecting members 25 about which the flexible conduit 26 is wound. The flexible conduit may be made of rubber, plastic or other suitable substance. The connecting members 25 are curved in order that the flexible conduit is not bent around sharp corners while on the reel. It will be apparent now that the reel 14 is rotatably mounted on the brackets 12 and 13 by means of the ball bearing assemblies 19 in the bearing sleeves 18 of the brackets.

The inner end of the flexible conduit 26 extends inwardly through an aperture 27 in one of the connecting members 25 and is provided with an externally threaded fitting 28 which engages in an internally threaded aperture in a coupling 29. The fitting 28 and the coupling 29 are secured together in fluid tight relation by a dock washer 30 threaded on the fitting 28 which compresses a gasket 31 against the flat upper surface of a boss 32 provided on the coupling. The coupling has an outwardly extending annular flange 33 which is secured to an annular ledge 34, formed in the shaft 24 of end disk 32 by an enlargement of the central bore 36, by bolts 37. An annular gasket 38 is interposed between the ledge 34 and the flange 33 to seal against the passage of fluid therebetween.

The coupling 29 is also provided with an annular inwardly extending flange 39 against which abuts the outwardly extending flange 40 on the inner end of a fitting 41. The flange 40 is of greater diameter than the bore 36 of the shaft 24 so that a packing 42 may be disposed in the annular space formed by the ledge 34, the flange 40, the coupling 29 and the fitting 41. The packing 42, which may consist of a plurality of packer rings, seals between the coupling 29, the fitting 41 and the shaft 24 to prevent leakage of fluid therebetween.

The bore 36 of the shaft 24 of the end disk 22 is enlarged at the outer end of the shaft to provide an annular ledge 43 and is threaded as at 44 to receive a gland nut 45 which has an inwardly extending flange 45a. A packing 45 is compressed between the flange 45a of the gland nut 45 and the ledge 43 to seal between the fitting 41 and the shaft 24. A resilient washer 46a is interposed between the outwardly extending flange 47 of the gland nut and the outer end of the shaft 24 of the end disk 22.

It will now be apparent that the shaft 24 may rotate in the ball bearing assembly 19 about the stationary fitting 41 and that the coupling 29 which is rigidly secured to the shaft by the bolts 37 will rotate with the shaft. Fluid may pass through the fitting 41, the coupling 29, and the fitting 28 into the flexible conduit 26 whatever the axial position of the reel 14 to the fitting 41. The packings 42 and 45 prevent leakage of fluid between elements which are movable relative to one another. The shaft 24 of the end disk 23 may obviously be a simple stub shaft extending into the bearing sleeve of the bracket 13 since it need only support one end of the reel.

Fluid is pumped into the fitting 41 by a pump 48 mounted on the base 11 and having an outlet

49 which is connected to the fitting 41 by a suitable assembly 50 of pipes and elbow joints. The pump is connected to a reservoir of fluid by a pipe 51 which is connected to the inlet of the pump, not shown, by a suitable assembly 52 of pipes and elbow joints. The pump is driven by an electric reversible motor 53 also mounted on the base 11.

The reel 14 is rotated by electric reversible motor 54 mounted on the base 11 and having a pulley 55 on its shaft 56. The shaft 24 of the end disk 22 is also provided with a pulley 55 which is rigidly mounted on the shaft 24 by means of a conventional slot and key 57 connection. A belt 58 connects the pulleys 55 and 56 so that the motor 54 causes the reel 14 to rotate.

In order that an operator may control the motors 53 and 54 while handling the nozzle 59 at the free end of the flexible conduit 26, which may be at a considerable distance from the base 11 when the flexible conduit is completely unwound off the reel 14, the flexible conduit is provided with four pairs 60, 61, 62 and 63 of flexible conductors which are embedded in the wall of the flexible conduit. The flexible conductors are preferably embedded far from the outer surface of the flexible conduit in order that abrasion and wear of the conduit will not readily expose the conductors. As shown in the drawing, the inner wall of the conduit is actually provided with ridges 64 which extend over the conductors.

The inner ends of the pairs 60, 61, 62 and 63 of flexible conductors are brought out adjacent the fitting 28, Figure 6, and extend through an aperture 65 in the end disk 22. The conductors 60a, 61a, 62a and 63a are connected to one another and to a slip ring 66 mounted on an annular mounting block 67 of non-conductive substance which is secured to the disk 22 by a plurality of screws 68. The conductors 60b, 61b, 62b and 63b are connected to the slip rings 69, 70, 71 and 72, respectively also mounted on the block 67.

A block 73 of non-conducting material is secured to the bearing ring 18 of the bracket 12 by bolts 74, one of which can be seen in Figure 6. The block 73 is provided with a plurality of recesses 75 each of which receives a coil spring 76 which biases a brush 77 slidably mounted in an aperture 78 of the plate 79 which is secured to the block 73 by screws 80.

As can be seen diagrammatically in Figure 7, the brushes 77 contacting the slip rings 71 and 72 are connected to two terminals *a* and *b* of the reel motor 54 while the brushes contacting the rings 69 and 70 and connected to two terminals *a* and *b* of the pump motor 53. The third terminal *c* of each motor is connected directly to one side of a direct current supply circuit 81 while the brush 77 contacting the slip ring 66 is connected to the opposite side of the supply circuit. The motors 53 and 54 rotate in one direction when their terminals *a* and *c* are connected across the supply circuit 81 and in the opposite direction when their terminals *b* and *c* are connected across the supply circuit.

The pump motor 53 is controlled by a pair of switches 82 and 83 while the reel motor is controlled by the switches 84 and 85. As can be seen in Figure 7, the terminals *a* and *c* of the pump motor 53 are connected across the supply circuit through the brush 77 contacting the slip ring 69, the conductor 60b, the switch 82, the conductor 60a, slip ring 66 and the brush 77 contacting the slip ring 66 when the switch 82

is depressed. The pump motor 53 will then rotate in one direction. If the switch 83 instead is depressed, the terminals *b* and *c* of the pump motor will be connected across the supply circuit and the pump motor will rotate in the opposite direction. The switches 84 and 85 will connect the terminals *b* and *c* and terminals *a* and *c*, respectively, across the supply circuit when actuated so that the direction of rotation of the reel motor 54 can similarly be controlled.

The switches 82 to 85 are mounted on a rectangular housing 86 mounted on the free end of the flexible conduit 26 adjacent the nozzle 59. The housing 86 has annular flanges 87 and 88 which are clamped to the flexible conduit by clamp rings 89 and 90, respectively, which are tightened by screws 91 and 92, respectively. The housing 86 is of non-conductive substance and has a bore 93 in each side which is closed by an apertured rectangular plate 94 of non-conductive material. The plates 94 are secured to the housing by screws 95. Each of the bores 93 is reduced to form a ledge 96 against which bears the spring 97 which biases the switch 82, 83, 84 or 85, as the case may be to open position. Each of the switches includes a circular contact plate 98 of a conductive substance which is adapted to contact the posts 99 and 100 to which a pair of the conductors 60, 61, 62 or 63 are connected. A push button 101 is secured to each circular plate 98 by a screw 102 and extends through an aperture 103 in the associated rectangular plate 94.

If desired, the rectangular plates 94 may be made of a flexible material, such as rubber and may be cemented to the housing and to the circular contact plates 98 to hermetically seal the switches so that any sparks occurring in the switches would not ignite inflammable vapors which may be present if the device is used to transfer gasoline or other highly volatile fuels.

The nozzle 59 may be of the conventional type having a rotatable vane 104 in its throat geared to an indicating mechanism 105 for indicating the quantity of fluid passed through the nozzle.

In such use as the loading of fuel oil into a storage tank of a residence, the device 10 may be mounted on a tank truck with the conduit 51 communicating with the reservoir of fuel oil in the tank of the truck. The truck is driven as close as possible to the storage tank and the driver of the truck then stops the truck and moves to the device 10. The nozzle 59 is lifted from the socket 106 and the switch housing is lifted from between the brackets 107 and 108 on the base 11 which serve to keep the switches clear of the base. One of the switches 84 or 85, say 84, which connects the reel motor across the supply circuit in such manner that the reel is rotated in a direction to unwind the flexible conduit 26 is actuated and the operator carries the nozzle away from the truck toward the storage tank. The reel motor 54 can be stopped and started as desired so that an unnecessary length of the flexible conduit is never unwound. When the nozzle is brought to the storage tank, the reel motor is stopped and the nozzle is inserted into the inlet of the storage tank. One of the switches 82 or 83, say 82, is depressed and causes the pump motor to rotate in such a direction as to cause the pump to move fuel oil from the truck tank to the storage tank. When the desired amount of fuel oil is transferred to the storage tank, the switch 82 is released and the nozzle is lifted out of the inlet of the storage tank. The

switch 83 is then actuated to cause the pump motor 53 to rotate in the opposite direction and cause the pump to draw the fuel oil remaining in the flexible conduit back into the truck tank.

5 The switch 85 is next actuated and causes the reel motor to rotate the reel in the direction necessary to wind the flexible conduit on the reel. The operator need only walk along carrying the nozzle as the flexible conduit is wound on the reel. When the conduit is fully wound on the reel, the nozzle is replaced in the socket and the switch housing 86 is replaced between the brackets 107 and 108.

15 It will be apparent from the above description that a single operator can control the pump and reel motors as he handles the nozzle. Moreover, it will be evident that the conductors controlling the motors can not foul since they are embedded in the flexible conduit. Neither are these conductors exposed to wear or abrasion due to their mounting in the flexible conduit.

20 It will be obvious to those skilled in the art that various changes and modifications can be made in the described and illustrated device without departing from the invention and, it is intended, therefore, in the appended claims to cover all such changes and modifications as fall within the true spirit and scope of the invention.

25 What is claimed is:

30 1. In combination: a rotatable reel; a motor for rotating said reel selectively in opposite directions; a pump having an outlet; an elongate flexible conduit having one end secured to the reel, said one end being connected to the outlet 35 of said pump; a motor for driving said pump to move fluid selectively in either direction through said flexible conduit, said conduit having a plurality of flexible conductors embedded therein and extending longitudinally thereof; a nozzle 40 at the other end of said flexible conduit; and a plurality of switches mounted on said flexible conduit adjacent said nozzle and connected to said conductors for selectively controlling the operation of said reel and pump motors, said conductors also being connected to said motors.

45 2. In combination: a rotatable reel mounted on a stationary structure; an electric reversible motor for selectively rotating said reel in opposite directions; a pump having an outlet; a flexible conduit having one end secured to said reel; means mounted on said stationary structure connecting said one end of said flexible conduit to said outlet of said pump; a motor for driving said pump to move fluid selectively in either direction through said flexible conduit, said conduit having a plurality of flexible conductors embedded therein and extending longitudinally thereof, said conductors having ends brought out adjacent said one end of said flexible conduit; co-operating means on said fixed structure and said reels connecting said ends of said conductors to terminals of said motors; a nozzle on the other end of said flexible conduit; and a plurality of switches mounted on the flexible conduit adjacent said nozzle, the other ends of said conductors being brought out adjacent said switches and connected thereto, said switches selectively controlling the operation of said reel and pump motors.

50 3. The device of claim 2 characterized in that said cooperating means comprise a plurality of slip rings mounted on said reel and a plurality of brushes mounted on said stationary structure, each of said brushes contacting one of said slip rings.

4. In combination: a rotatable reel; a motor for rotating said reel selectively in opposite directions; a pump having an outlet; an elongate flexible conduit having one end secured to the reel, said one end being connected to the outlet of said pump; a motor for driving said pump to move fluid selectively in either direction through said flexible conduit, said conduit having a plurality of flexible conductors embedded therein and extending longitudinally thereof; a nozzle at the other end of said flexible conduit; and a switch housing having a plurality of switches mounted on said conduit adjacent said nozzle and connected to said conductors for selectively controlling the operation of said reel and pump motors, said conductors also being connected to said motors for connecting said motors across a supply circuit when said switches are actuated.

5. A pumping device comprising: a reel having an electric driving motor rotatably mounted on a fixed structure; a pump having an electric driving motor; a flexible conduit having one end secured to said reel and connected to said pump; a plurality of conductors in the wall of said flexible conduit extending longitudinally thereof, said conductors having opposite exposed ends

5 at said one end of said conduit and at the other end of said conduit; a plurality of slip rings and a plurality of brushes, each of said brushes contacting one of said slip rings, for connecting said exposed ends of said conductors to said motors; and control means mounted adjacent the other end of said flexible conduit for connecting exposed ends of the conductors for controlling the operation of said motors.
